UNITED STATES PATENT OFFICE.

ALBERT F. RANDOLL, OF ST. LOUIS, MISSOURI, ASSIGNOR OF ONE-FOURTH TO JULES A. BAKER AND ONE-FOURTH TO JOHN J. BAKER, BOTH OF ST. LOUIS, MISSOURI.

WARDROBE TRUNK.

Application filed October 27, 1923. Serial No. 671,271.

To all whom it may concern.:

- Be it known that I, ALBERT F. RANDOLL, a citizen of the United States, residing at St. Louis, Missouri, have invented a certain 5 new and useful Improvement in Wardrobe Trunks, of which the following is a full, clear, and exact description, such as will enable others skilled in the art to which it appertains to make and use the same.
- 10 This invention relates to wardrobe trunks. One object of my invention is to provide a wardrobe trunk that is equipped with an inexpensive drawer locking mechanism of simple design that securely holds all of the 15 drawers of the trunk closed and prevents any of said drawers from being twisted or turned in such a way as to partially open the drawer without, however, releasing it from the locking mechanism.
- 20 Another object is to provide a wardrobe trunk that is equipped with a drawer locking mechanism that will not be affected by warping of the drawers or overpacking of the drawers and which is so constructed that 25 if one drawer is open and the other drawers are locked, the movement of the open drawer into its closed position causes it to be locked automatically.

Other objects and desirable features of 30 my invention will be hereinafter pointed out.

Figure 1 of the drawings is a perspective view of a portion of a wardrobe trunk equipped with a drawer locking mechanism 35 constructed in accordance with my invention, the drawers being removed.

Figure 2 is a side elevational view of said trunk, partly broken away, and showing some of the drawers in longitudinal section, 40 so as to illustrate how the locking devices act on the rear end portions of the drawers; and

Figure 3 is an enlarged view of one of the 45 drawer locking devices and the releasing bar which renders said device inoperative.

Briefly stated, my invention consists of a 50 wardrobe trunk equipped with sliding drawers a plurality of pairs of locking devices, each of which is associated with a drawer and arranged to engage the rear end portion 55 of the drawer at two widely separated points, thereby holding the drawer in its locked position, and preventing it from be-

ing twisted or turned sufficiently to obtain 55 access to the drawer when it is locked, and a concealed controlling member combined with said locking devices in such a way that it can be manipulated from the front of the drawers to render all of said devices inoperative simultaneously. In the drawings A 60 designates the drawer section of the trunk, B designates a plurality of sliding drawers arranged in said section in superimposed relation, and C designates a drawer arranged at the upper end of the drawer section A 65 above the drawers B. The drawer C is equipped with a key-controlled lock 1 of any suitable design, by which said drawer can be locked in its closed position, and the drawers B are retained in their closed position by 70 a locking mechanism composed of a plurality of pairs of locking devices 2 and a controlling member 3 for said locking devices arranged inside of the drawer section A of the trunk in such a way that it can be manipulated only when the drawer C is open. 75

The locking devices 2 are preferably so constructed and arranged that they will enter notches formed in the sides x of the drawers B adjacent the rear end walls y of said drawers, as shown in Figure 3, and while the particular design of said locking devices 2 may vary greatly without departing from the spirit of my invention, I prefer to construct said locking devices from 80 flat bars of spring metal and provide each of said devices with a hook-shaped portion 85 that is adapted to embrace the upper edge of the rear end wall y of the drawer with which it co-operates. In the form of my 90 invention herein illustrated the locking devices 2 are connected to the slides or supports 4 on the side walls of the drawer section A of the trunk at the rear ends of said supports, as shown in Figure 1, so that they 95 will engage the two rear corner portions of the drawer. Owing to the fact that each of the drawers B is retained in its closed position by two locking devices 2 that engage the rear end portion of the drawer adjacent the side walls of the drawer, it will be impossible for a person to twist or turn any one of the drawers B sufficiently to gain 100 access to same, as is possible with many of the types of drawer locking mechanisms now used in wardrobe trunks. Moreover, warp- 105

ing, buckling or bulging of the walls of the drawers, due to overpacking or from other causes, will not affect the drawer locking mechanism, as the drawer holding devices 5 engage the rear corners of the drawers which are not apt to be affected by warping or buckling of the side walls or back walls of the drawers.

Various means may be provided for transmitting movement from the controlling member 3 to the locking devices 2 to render said locking devices inoperative, but I prefer to use two flat, thin releasing bars 5 that are slidingly mounted on the rear wall of the drawer section A of the trunk and which have their upper ends connected with a shifting bar 6 in such a way that when said shifting bar is moved in one direction, for example, to the left, by manipulating the controlling member 3, the releasing bars 5 will move downwardly, thus causing the locking devices 2 to become operative, and when said shifting bar 6 is moved in the opposite direction, for example, to the right, by manipulating the controlling member 3, said releasing bars 5 will move upwardly, and thus disengage the locking devices 2 from the drawers B. In the form of my invention herein illustrated each of the releasing bars 5 is provided with a plurality of lugs 5^a arranged in such a position with relation to the locking devices 2 at one side of the drawer section A of the trunk that they will engage the hook-shaped portions 2^a of said locking devices and move said locking devices upwardly into the position shown in dotted lines in Figure 3 when the controlling member 3 is manipulated to raise the releasing bars 5. The controlling member 3 is arranged on the underside of the top wall of the drawer section A of the trunk and is pivotally connected at 7 to said top wall, and the connection between said controlling member and the shifting bar 6 may be formed conveniently by a projection 8 on said shifting bar that enters a notch or elongated slot 3^a in the rear end of said controlling member. The shifting bar 6 is slidingly mounted in guides 9 on the rear wall of the drawer section of the trunk, and said shifting bar is provided adjacent its ends with pins 10 that enter inclined slots 11 in the releasing bars 5 which are so disposed that lateral movement of said shifting bar 5 in one direction raises the releasing bars 5 and lateral movement of said shifting bar in the opposite direction depresses the releasing bars.

When the drawers B and C are closed and the drawer C is locked it is impossible to open any of the drawers B or twist or turn any of said drawers B in such a way as to partially open same, due to the fact that each of the drawers B is held in its closed position by a pair of locking devices 2 that

are positioned in notches in the side walls of the drawers B adjacent the rear end walls of said drawers. To open any of the drawers B it is necessary to first release and open the drawer C and then manipulate the controlling member 3 in such a way as to move the releasing bars 5 upwardly, thereby causing the lugs 5^a on said bars to disengage the locking devices 2 from the drawers B.

A drawer locking mechanism of the construction above described is inexpensive to manufacture and easy to install, and as each of the drawers B governed by said mechanism is retained in its closed position by two locking devices that engage the rear corners of the drawer at widely separated points, it is impossible for a dishonest person to gain access to any of the drawers B when the locking devices 2 are in their operative position, and there is little liability of the drawer warping, buckling or bulging to such an extent as to affect the drawer locking mechanism. Still another desirable feature of a wardrobe trunk equipped with such a drawer locking mechanism is that any one of the drawers B can be moved into its locked position when the other drawers B are locked without manipulating the controlling member 3. For example, if one of the drawers B is left open after the remainder of the drawers B and the drawer C have been closed and locked, the operation of moving said open drawer B into its closed position causes it to become locked automatically, due to the fact that the locking devices 2 which are associated with said open drawer are in a condition to spring into the notches in the rear end portion of the drawer when the drawer is moved into its closed position. This is a very desirable feature of a wardrobe trunk, for it frequently happens that a user, in closing and locking the drawers, carelessly leaves one of them open. With drawer locking mechanisms of the kind now generally used on wardrobe trunks this would necessitate opening the drawer equipped with the key-controlled lock and then manipulating the controlling member governing the concealed locking devices, so as to permit the open drawer to be moved into its closed position. My invention overcomes the necessity of opening the key-controlled drawer and manipulating the controlling member in an instance of the kind referred to, because my improved drawer locking mechanism is equipped with resilient locking devices that can flex sufficiently to move into locking engagement with a drawer that is being moved from its open into its closed position, when the remainder of the drawers of the set are locked.

Having thus described my invention, what I claim as new and desire to secure by Letters Patent is:

A wardrobe trunk provided with a plu-

rality of sliding drawers arranged in superimposed relation, a key controlled lock for retaining one of said drawers in its closed position, a plurality of pairs of resilient locking devices for retaining the other drawers in their closed position arranged so that the locking devices co-operating with

each drawer engage the rear corners of the drawer, and a manually-operable controlling member accessible when the key locked drawer is opened for rendering said resilient locking devices operative and inoperative.

10

ALBERT F. RANDOLL.
